SUCTION CLEANER

Donald G. Smellie, Canton, Ohio, assignor to The
Hoover Company, North Canton, Ohio, a cor-
poration of Ohio

Application January 5, 1938, Serial No. 183,479

6 Claims. (Cl. 15—6)

The present invention relates to suction cleaners in general and particularly to new and novel improvements in surface-agitating means in a suction cleaner. More particularly the invention comprises a suction cleaner in which rotary agitating means and reciprocating agitating means are removably mounted and are positively driven in a new and novel manner.

It is an object of the present invention to provide a new and improved suction cleaner. It is another object of the invention to provide a new and improved suction cleaner embodying rotary and reciprocating agitating means. A still further object of the invention is to provide a suction cleaner in which the reciprocating agitating means are driven by new and novel means from the rotary agitating means. Still another object of the invention is to provide a suction cleaner in which the rotary agitating means and the reciprocating agitating means are mounted in an improved manner which results in better operation and greater ease of removal and replacement. Still another object of the invention is to provide new and improved means by which the reciprocating agitator is actuated from and upon the rotation of the rotary agitator which is driven from the power means of the cleaner. Another object of the invention is to provide a suction cleaner in which the reciprocating beater elements are carried by the nozzle lip construction while the actuating means therefor are carried by the rotary agitator unit. A still further object of the invention is to provide a suction cleaner in which reciprocated beater elements pivot about an axis which is substantially in the plane of surface agitation. These and other more specific objects will appear upon reading the following specification and claims and upon considering in connection therewith the attached drawings to which they relate.

Referring now to the drawings in which preferred embodiments of the present invention are disclosed, and in which the same reference character refers to the same parts throughout:

Figure 1 is a side elevation of a modern suction cleaner with the nozzle side wall broken away to show the agitating means positioned therein;

Figure 2 is a bottom view of the nozzle of the cleaner shown in Figure 1;

Figure 3 is a section on the line 3—3 of Figure 2, and shows the rotating support for the rotary brush, the pivotal mounting of the reciprocating beating elements, and the drive means by which

the reciprocating agitating elements are actuated by the rotary agitator;

Figure 4 is a vertical section upon the line 4—4 of Figure 3 and again shows the means by which the rotary brush drives the reciprocating beater elements;

Figure 5 is a section upon the line 5—5 of Figure 3 and discloses the means, there being one at each nozzle end wall which seats the rotary agitator within the nozzle;

Figure 6 is a section through the nozzle with the cleaner inverted, the lip frame pivoted therefrom, and the rotary brush unit partially removed from the nozzle;

Figure 7 is a section through a cleaner nozzle showing a second preferred embodiment of the invention in which the agitator-carrying lip frame is formed as an integral part of the removable bottom plate for the air passageway leading from the nozzle to the suction-creating fan chamber;

Figure 8 is a section similar to Figure 3 but through the third preferred form of the invention in which the rotary brush unit can be pivoted from the nozzle with the lip frame;

Figure 9 is a view of the third embodiment of the invention showing the rotary brush unit and the lip frame in the displaced position;

Figure 10 is a section upon the line 10—10 of Figure 8 and shows the lip frame retained in place within the nozzle.

In the modern suction cleaner the cleaning effectiveness of the moving air stream is supplemented by surface agitating means. These agitating means may preferably comprise a rotary brush and reciprocating rigid beater elements. The latter deliver to the surface covering a positive beating action which dislodges therefrom deeply embedded foreign material while the former functions to straighten the pile to give to the covering an improved appearance. The rotary brush can well be rotated from the shaft of the driving motor of the cleaner and is preferably positioned within the nozzle. According to the present invention the reciprocating agitator is actuated by the rotary agitator and the two agitating means are both positioned within the cleaner nozzle where they are supported and interconnected in a new and novel manner.

An advantage of the invention lies in the fact that the reciprocating rigid beater elements are pivoted about an axis which lies substantially in the plane of surface agitator thereby resulting in a beating blow which is normal to the surface covering.

Referring again to the drawings and to Figures 1 to 6, in particular, the first preferred form of the invention is disclosed. A suction cleaner comprising a nozzle 1, a fan chamber 2 with an exhaust outlet 3, together with a motor casing 4, also includes an air passageway 5 formed with a removable bottom plate 6 which connects the nozzle 1 to the fan chamber 2. A dust bag 7 is removably secured to the exhaust outlet 3 by manually operable means 8 and a pivoted handle 9, which includes position-controlling means 10, provides means by which the operator may propel the machine over a surface covering undergoing cleaning. The cleaner rests upon front and rear supporting wheels 11, 11 and 12, 12 respectively. An unshown driving motor within the motor casing 4 drives the suction-creating fan 15 within the fan chamber 2 while the extended end of the motor shaft 16 passes downwardly into the air passageway 5 where it is formed as a pulley surface 17 to seat a power-transmitting belt 18 which extends forwardly into the nozzle through the air passageway.

The foregoing, together with the manually operable means 19 by which the rear wheels may be raised and lowered to vary the height of the nozzle 1 above the surface covering completes the cleaner structure which is purely conventional.

A reciprocating agitating unit 22, perhaps best illustrated by itself in Figure 6, is positioned within the nozzle and comprises a lip frame including a forward transverse surface-contacting element 23, which functions as the front lip of the nozzle 1, and rearwardly extending side arms 24, 24 each of which includes a flat surface contacting part 25. A reciprocating agitator comprising end plates 26, 26 and rigid elongated beater elements 27, 27 completes the unit and is pivotally mounted upon the lip frame by pivot pins 29, 29 mounted in the arms 24, 24 of the frame. As these agitating elements 27, 27 are adapted to move upwardly and downwardly and as they extend beyond the side arms 24, 24 of the lip frame, each arm is recessed at 28, 28 so as not to interfere with such movement. The entire reciprocating agitator unit is pivotally mounted to the end walls of the nozzle 1 upon pivot pins 30, 30 positioned immediately above the lip 23.

Unintentional displacement of the reciprocating agitating unit downwardly from the nozzle is prevented by the extension of the lip frame side arms 24, 24 over the rear lips 33 of the nozzle which is formed as a part of the removable bottom plate 6 of the air passageway 5. The bottom plate itself is secured to the underside of the nozzle casing in the manner shown in Figure 5 in which a rounded abutment 34 at the nozzle end seats upon a nozzle carried rounded shoulder 35 to permit the rear end of the plate to be raised against the underside of the fan chamber 2 where it is secured in place by suitable manually operable latching means 36, indicated in Figure 1. The presence of a rubber gasket 37 between the bottom plate 6 and the nozzle casing insures that the parts will make a good seal and that unintended dislocation will be prevented.

Also within the nozzle 1 is a rotary brush unit the principal element of which comprises the rotary cylindrical body 40 which is formed substantially midway between its ends with a pulley groove which seats the power-transmitting belt 18 from the motor shaft. Agitator body 40 is suitably provided with agitating element seats 41 etc. which removably seat in a well known manner, agitating elements such as brushes 42,

42. Each end of agitator body 40 is closed by an end plate 44 which is counterbored interiorly to seat a ball bearing 45 and is formed exteriorly with an eccentric 46. A through supporting shaft 48 extends through the body 40, through the end plates 44, 44 and eccentrics 46, 46 and with its flattened ends seats within vertical slots 49, 49 at each nozzle end wall. A pivoted spring 50 extends across each slot 49, being movable within limits set by the stops 51, 51 and upon being contacted by the shaft end and forced against the upper stop 51 exerts a resilient downward force thereon.

The rotary agitator is supported within the nozzle, and prevented from unintentional downward displacement therefrom, by support housings 55, 55 which enclose the eccentrics 46, 46 and the edges of each of which seat within a channel or groove 56 which extends around the nozzle's interior. Each housing 55 comprises principally a plate 57 the upper three sides of which seat within the groove 56, while the bottom side thereof is supported by the flat surface-contacting portion 25 of the reciprocating agitating unit's side arm 24. Plate 57 is centrally bored to enclose the end plate 44 adjacent the eccentric 46 without making contact therewith and also carries a thread guard 58 which encloses the end of the agitator body. Upon the plate 57 screws 61, 61 etc. removably secure an open bottom cup-shaped member 60 the outer wall of which seats upon shaft 48 where it is retained by a threaded nut member 62. As the main portion of member 60 is spaced from the main plate 57 there is formed therebetween a housing which encloses the eccentric 46 and within which is positioned the power-transmission means by which the reciprocating agitator is actuated upon the rotation of the rotary brush.

Seated upon each eccentric 46, with only a sleeve bearing therebetween, is a collar 65 from diametrically opposed points on which extend pins 66, 66. An actuator plate 68 is pivotally supported by housing plate 57 through a pivot 69, which is aligned with the pivots 29, 29 and is formed with an upwardly extending central portion which is cut out to enclose in spaced relationship the collar 65 and its pins 66, 66, which seat within bearings 70, 70 on the actuator. Upon each side of its pivot pin 69 the actuator plate 68 is formed with an arm 72 which extends parallel to the end plates 26, 26 of the reciprocating agitator. At the extremity of these arms 72, 72 are formed resilient seats 73, 73 which contact the elements 27, 27. Obviously the rotation of the eccentric 46 will translate the collar 65 with the pins 66, 66 sliding within the bearings 70, 70 while pivoting the actuator plate 68 about its pivot 69.

The operation of the invention constructed in accordance with this first embodiment of the invention is as follows: Upon being placed in operation, as by the operator closing an unshown motor-controlling switch in the usual manner, the unshown motor rotates and drives through its shaft 16 the suction-creating fan 15 and the belt 18. The rotation of the fan 15 creates a reduced pressure which is effective within the nozzle 1 to draw cleaning air therethrough, and to lift the surface covering undergoing cleaning upwardly into contact with the lips 23 and 33. The power transmitted to the belt 18 results in the rotation of the rotary agitator the agitating elements 42 of which contact the surface covering between the nozzle lips 23 and 33. As the

body 40 rotates the eccentrics 46 at its ends reciprocate the actuators 68, 68 through an angle which is equal to twice the eccentricity of the eccentrics 46, 46. The actuator plates 68, 68 which are in direct contact with the beating elements 27, 27, are pivoted upon the pivot pins 69, 69 as is illustrated in Figure 3, resulting in the reciprocation of those beater elements through an arc which is normal to the surface covering at the point of contact therewith.

In the event that it is necessary to remove the rotary agitating unit comprising the rotary brush and the power-transmission means which are connected thereto, it is only necessary first to remove the bottom plate 6 of the air passage-way 5. This is accomplished by moving the latch 36 to permit of the downward displacement of the rear end of the plate after which the abutment 34 at its forward end can be disengaged from its overlapping relationship with the shoulder 35. The displacement of the bottom plate 6 also removes the rear nozzle lip 33, which is formed thereon, and thereupon the side arms 24, 24 of the reciprocating agitating unit can pivot outwardly from the nozzle in the manner shown in Figure 6. Thereafter the rotary agitator assembly can be displaced outwardly from the nozzle, also in the manner indicated in Figure 6.

Replacement is exactly the reverse operation, the rotary agitator assembly is inserted into the nozzle, the edges of each plate 57 seating within a channel 56 formed therefor, and each end of the agitator shaft 48 seating within a slot 49 in the nozzle end wall. Near the upper end of each slot 49 the resilient spring 50 contacts the shaft to oppose resistingly any further movement and resiliently forces the bottom edge of plate 57 against the surface-contacting parts 25, 25 of the reciprocating agitator unit, and specifically of the pivoted lip frame, when that part is pivoted into the nozzle from its displaced position. Thereafter, and upon the positioning of the bottom plate 6 by inserting the abutment of abutment 34 over the shoulder 35 and the pivoting of the rear end thereof upwardly to permit the latch 36 to be engaged, the entire assembly is positively secured in operative relationship.

Referring now to Figure 7, in particular, the second preferred embodiment of the invention is disclosed. This form differs from the first embodiment essentially in that the bottom plate 6 is fixedly and permanently secured to the rearwardly extending side arms 24, 24 of the lip frame whereas in the first embodiment the lip frame and the bottom plate were separate, the bottom plate functioning to prevent the downward pivotal displacement of the lip frame when in place. The operation of this form of the invention is identical with that first described and the difference in structure is important only when the nozzle is to be opened to displace the agitating means therefrom. In this embodiment the operation of the latch 36 at the rear of the bottom plate 6, the latch being shown in Figure 1, permits the bottom plate together with the lip frame comprising the front nozzle lip 23 and the rearwardly extending side arms 24, 24, to pivot outwardly about pins 30, 30 and when in the open position the rotary agitator unit is removed precisely as in the first embodiment. The cleaning operation of all parts are identical with their operation in the first embodiment.

Referring now to Figure 8, 9 and 10, in particular, the third preferred embodiment of the invention is disclosed which distinguishes from the

first two embodiments in the manner of insertion and removal of the agitator units from the nozzle. According to this form of the invention a rotary agitator unit is pivoted from the nozzle directly with a reciprocating agitator unit which includes the lip frame and the reciprocating agitator.

The reciprocating agitator unit 22 of this embodiment includes the front nozzle lip 23 with its rearwardly extending side arms 24, 24 which is pivoted upon pivot pins 30, 30 above the front lip just as in the first embodiment. Also, as in the first embodiment, downward displacement of the unit is prevented by the rear lip 33 carried by the separately detachable bottom plate 6. In the first embodiment, however, the flattened ends of the agitator shaft extend into slots 49, 49 formed in the end walls of the nozzle, whereas in the present embodiment each lip frame arm 24 is itself provided with a shaft-receiving slot 75 which opens upwardly and which is adapted to receive the end of the agitator shaft when the frame is pivoted from the nozzle, as illustrated in Figure 9. Cooperating with the slot 75 is a wire spring 76 which extends across its lower extremity to lie over a supporting pin 71. With the agitator in place and the shaft ends positioned within the slots 75, 75 the shaft actually rests upon the springs 76, 76 which urge the agitator, together with the housings 55, 55 at the ends thereof, upwardly to retain the upper edges of the plates 57, 57 within their channels 56, 56 at each end of the nozzle. In this embodiment the rear contour of the grooves 56, 56, as well as the rear edge of each plate 57, 57 have been shaped to permit the unit to pivot outwardly from the nozzle about the supporting pins 30, 30 without binding.

In operation this form of the invention functions exactly in the manner of the first embodiment. The distinctions in structure are important upon the assembly and disassembly of the device. To disassemble this embodiment of the invention the bottom plate 6 is removed, as in the first embodiment, and thereafter the lip frame is pivoted downwardly about the pins 30, 30. With the frame in this embodiment, however, comes the rotary brush unit to the position illustrated in Figure 9, after which the rotary agitator unit can be displaced from the frame by sliding the shaft 48 from the slots 75, 75. The springs 76, 76 contacting each end of the agitator shaft 48 maintain a vibrationless fit between the housings at the end of the agitator and the nozzle within which they fit.

In each embodiment of the invention it is characteristic that the pivotal axis of the reciprocating vertical beater elements 27, 27 lie substantially in the plane of surface contact of those elements which results in an operation in which the blow delivered to the surface covering is substantially normal to that surface thereby eliminating the horizontal components of movement.

I claim:

1. In a suction cleaner, a nozzle, a rotary agitator unit displaceably positioned in said nozzle and including a rotary agitator and power transmission means positioned axially adjacent said rotary agitator to transform rotary into reciprocating motion, and a vertically reciprocating agitator removably positioned in said nozzle including a reciprocating agitator, underlying said rotary agitator unit and retaining it in place in said nozzle.

2. In a suction cleaner, a nozzle, a rotary brush formed with an eccentric at its end, a collar with a trunnion seated on said eccentric, a reciprocating agitator pivoted substantially in the plane of surface agitation, and an actuator slidingly enclosing said trunnion and connected to said reciprocating agitator to reciprocate the latter upon the rotation of the brush.
3. In a suction cleaner, a rotating member, an eccentric rotatable with said member, a collar formed with trunnions carried by said eccentric, a pivoted actuator slidingly enclosing said trunnions and adapted to be reciprocated about its pivotal axis upon the rotation of said eccentric, a reciprocating agitator comprising spaced beater elements mounted for pivotal movement about an axis parallel to the axis of said actuator, said actuator being formed with resilient seats to contact and actuate said agitator.
4. In a suction cleaner, a nozzle, a rotary agitator unit in said nozzle including a rotary agitator, stationary removable supporting housings at each end of said agitator seating said agitator in said nozzle, and motion-transforming means in said housings to transform rotary to reciprocating motion; and a reciprocating agitator unit in said nozzle including reciprocating agitating elements connected to said motion-transforming means and actuated thereby and means to retain said rotary agitator unit in said nozzle.
5. In a suction cleaner, a nozzle, a rotary agitator unit in said nozzle including a rotary agitator, a housing at each end of said agitator, an eccentric rotatable with said agitator in said housing, a trunnioned collar in said housing, and an actuator pivoted in said housing and slidably enclosing the trunnions of said collar; and a reciprocating agitator unit including a reciprocating agitating element connected to said actuator, and means to retain said rotary agitator unit in said nozzle.
6. In a suction cleaner, a nozzle, a rotary agitator including a stationary supporting shaft and a rotary body in said nozzle, a stationary housing fixedly secured to the stationary shaft at the end of said body, an eccentric actuated by said body extended into said housing, an actuator pivoted to said housing and operatively connected to said eccentric, means to secure said housing in said nozzle to position said rotary agitator and said actuator, and a reciprocating agitating element pivoted at the end of said rotary agitator for reciprocation with a vertical component and operatively connected to said actuator.

DONALD G. SMELLIE.
